FIREARM

Ralph H. Pike, Kalispell, Mont.

Application October 21, 1938, Serial No. 236,328

1. Claim. (Cl. 42—69)

This invention relates to firearms and more particularly to a trigger spring tensioning device of the type described in my application for patent entitled Firearm, filed January 4, 1938, Serial No. 183,375, Patent No. 2,143,028, January 10, 1939.

An object of this invention is to provide a self-setting trigger which may be adjusted to any predetermined weight of pull through the medium of a screw having a deep spiral thread receiving loop of the weight control spring and adapted to emit an audible click every quarter turn to announce a change in weight of pull within a preferred range of from $\frac{1}{2}$ pound to more than $2\frac{1}{2}$ pounds in steps of about $\frac{1}{4}$ pound per click.

A further object is to provide apparatus of this type which will unfailingly set itself for the weight selected each time the bolt is closed and will be proof against jar-off at any weight of pull.

A further object is to provide apparatus of this type which will be formed of a few strong simple and durable parts, which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a side elevation of a bolt action rifle, with portions broken away, to expose a trigger spring tensioning device constructed in accordance with the invention.

Figure 2 is a fragmentary plan view of the trigger guard plate and parts carried thereby including the flipper, trigger, and control springs.

Figure 3 is a perspective view of the trigger, weight controlled screw and control springs.

Figure 4 is a perspective view of the sear.

Figure 5 is a perspective view of the sear extension finger.

Figure 6 is a perspective view of the flipper, and its resetting spring.

Figure 7 is a perspective view of the weight controlled screw.

Referring now to the drawing in which like characters of reference designate similar parts in the various views, 10 designates a bolt action rifle. In carrying out the invention a substantially straight sear 11 is provided on the top near the forward end with a hinge eye 12 to which a hinge

pintle 13 is passed into the side plates of the lock mechanism. A helical spring 14 is housed in a recess 15 formed in the top of the compartment and bears upon the top of the front end of the sear to constantly urge the rear end of the sear 5 upwardly.

The rear end of the sear is provided with a shoulder 16 which is beveled at the rear corner to provide an abutment face 17 which engages a beveled abutment face 18 on the front lower edge 10 of the cocking piece nose 19. The beveled faces 17 and 18 are inclined at an angle of about 30 degrees relative to the axis of the barrel so that when the bolt 20 is cocked there will exist a forward component of force and also a downward 15 component of force at the constant faces. The downward component of force tends to force the sear downwardly and is resisted by the sear extension finger 21.

The sear extension finger 21 is received at the 20 upper end between hinge ears 22 which extend downwardly from the bottom of the rear end of the sear, and a pivot pin 23 is passed through the finger and ears to pivotally mount the finger on the sear. The top face of the finger is spaced 25 from the bottom face of the sear to provide sufficient clearance for the finger to pivot relatively to the sear. A helical spring 24 is mounted in a vertically extending opening 25 in the bottom face of the sear and bears against the top face 30 of the extension finger forwardly of its pivot pin 23 to hold the finger in engagement with the flipper 26.

The flipper 26 is substantially triangular in contour and is provided with two upper faces 35 27 and 28 of respectively different gentle slopes forming a shoulder 29 between them against which the lower end of the sear extension finger is lodged. The flipper is provided with a rearwardly extending finger 30 having a longitudinal slot 31 therein, the rear wall 32 of the slot being sloped downwardly and rearwardly to slidably receive a similarly shaped surface 33 on the trigger when a hook 34 on the trigger is engaged with the top face of the finger 30, with a lap 45 of about $\frac{1}{16}$ of an inch, to securely lock the flipper against downward thrust of the sear extension finger until the trigger is pulled.

The flipper is normally held in position to receive the sear extension finger through the medium of a U-shaped spring 35 which is engaged in a notch 36 in the rear face of the flipper and has legs looped around a pivot pin 37 which is passed through the flipper and into the top plate 38 of the trigger guard 39. The free ends of

the legs extend forwardly from the pivot pin and bear against the top plate of the trigger guard. Pressure of the spring on the flipper instantly returns the flipper to normal position 5 after each actuation by the trigger.

The trigger 40 is provided with a finger 41 which underlies the finger 26 of the flipper. A pivot pin 42 is passed through the finger and into the top plate 38 of the trigger guard to pivotally mount the trigger. A U-shaped spring 43 is engaged in a notch 44 in the top face of the finger 41 and the legs are trained underneath the pivot pin 42 and directed forwardly to bear at the free ends against the top plate 38 of the trigger guard. The spring exerts a rearward pressure upon the trigger rearwardly of the pivot pin 42 to assist the weight spring hereinafter described in returning the trigger to normal position to engage the hook 34 with the flipper after each actuation.

The front face of the trigger is cut away to provide a recess 45 in which is rotatably mounted a weight control screw 46 having a deep worm thread 47. The screw inclines rearwardly in the recess. A U-shaped weight control spring 48 is engaged with the thread of the screw and the legs are passed rearwardly and looped around the pivot pin 42 of the trigger, thence directed forwardly to bear with the free ends of the top plate 28 of the trigger guard. This spring resists pull upon the trigger and controls the weight of pull required to release the trigger from the flipper. The screw 47 is rotated through the medium of a screw driver inserted in a kerf 49 of the screw to feed the bight of the spring downwardly or upwardly on the thread of the screw to respectively increase or diminish the tension of the spring and correspondingly vary the weight of pull required to actuate the trigger and dislodge the sear extension finger 21 from the flipper.

A continuous groove 50 is formed circumferentially in the head of the screw as best shown in Figure 7 and preferably four equally spaced notches 51 are formed in the bottom of the groove. The groove receives a plunger 52, best shown in Figure 1, which is mounted in a recess 53 formed in the trigger at a right angle to the axis of the weight control screw 46. A helical spring 54 is disposed in rear of the plunger and is held under tension against the plunger through the medium of a screw plug 55 which closes the outer end of the recess. The plunger drops into the notches 51 successively as the screw is rotated 50 and provides four definite stops per turn of the screw with respective audible "clicks" as the

plunger rides from the groove into the notches. These stops can also be felt through the screw driver at the completion of each quarter turn of the screw.

Behind the trigger a screw 56 is threadedly engaged in a recess 57 formed in the trigger guard and bears against the lower face of the finger 41 in rear of the pivot pin 42. By screwing the screw 46 in or out the creep or overlap of the hook 34 of the trigger with the finger 26 of the flipper may be adjusted.

When the trigger is pulled against the tension of the weight control spring 48, downward pressure of the sear extension finger 21 turns the flipper slightly, as indicated by the arrowheads in Figure 1, and thus dislodges the sear extension finger from the shoulder 29. The sear being thus released the cocking nose 19 passes instantly over the shoulder 16 of the sear to fire the gun. Immediately after the dislodgement of the sear extension finger the controlling spring 35 of the flipper returns the flipper to normal position.

The trigger cannot be pressed rearwardly enough to interfere with the operation as the upper face of the finger 41 contacts the stock, or the lower end of the trigger contacts the guard.

From the above description it is thought that the construction and operation of the invention will be fully understood without further explanation.

What is claimed is:

In a firearm, a pivoted spring pressed trigger, a pivoted spring pressed flipper, interlocking means between the trigger and flipper yieldably holding the flipper in set position, a sear, interlocking means between the sear and flipper engageable by movement of the flipper under impulse of the trigger, after release of the first named interlocking means to release the sear, a weight control spring connected to the trigger and exerting pressure against the trigger to hold the first named interlocking means in operative position, a weight control screw having a worm thread engaging said spring to vary tension on the spring, said screw having a head provided with a circumferential groove, there being notches in the bottom of said groove, and a spring pressed plunger disposed laterally of the screw head and engageable in said groove and notches to provide audible "clicks" as the plunger rides from the groove into the notches during rotation of the screw.
